TIME STUDY TRAINING APPARATUS

Phil Carroll, Jr., Maplewood, N. J.

Application November 1, 1947, Serial No. 783,601

10 Claims. (Cl. 35—39)

1

The invention relates to educational apparatus for use in training timestudy engineers to enable them to read a decimal-minute watch or similar short time sweep hand indicator correctly.

It is the present practice with timestudy engineers to observe and make a time chart of the actions of a skilled or average workman doing a piece of routine work. The performance of operations on a piece of work not infrequently involves a number of separate acts or movements, known in the art as elements, and which total number of elements is hereinafter sometimes referred to as an operation. Ordinarily the timestudy engineer holds in the palm of his left hand a pad of paper and between his fingers a decimal minute stop watch or equivalent short time sweep hand indicator, and in his right hand he holds a pencil poised on the pad. He observes the termination of each act, step, hand movement, event or element performed by the workman in completing the operation under observation while he holds the watch in line with his eye and with the work under observation. The engineer presses the watch starter button at the end of each preceding event or element and thus at the beginning of each subsequent element; notes the reading of the watch sweep hand and jots down on the pad the number of hundredths of a minute consumed during each particular event or element of the complete operation. The watch of course snaps back to its zero position at each pressing of its starter button and immediately starts again on its travel about the watch dial. The stop-start button is again pressed at the termination of a second step, event or element and so on, the engineer pressing the watch controlling button at the end of each element in the complete sequence of steps until the operation under observation is completed. Usually this is done several times to obtain the correct answer to the basic inquiry as to how much time was consumed in performing the several elements which made up the complete operation.

It has been found in practice that there is a material variation in the observations of different engineers or other testers while observing and recording identically the same operation even under those conditions where the operation is performed mechanically and without human effort. Also the accuracy of observation varies from time to time among different observers and is apparently dependent largely upon the skill of the tester in his ability to coordinate the actual instant of time when an observed element terminates, with such terminations as are indicated by his watch read-

ings. The highly skilled tester is quite accurate, even to the hundredth of a minute in noting the lapsed time duration of elements and this in turn is dependent upon the observer's skill in mentally anticipating the termination of each step or element, so that he is able to press the watch button, more or less, exactly at the termination of each step and the greater the skill developed in anticipating the actual termination of each element the less becomes any time lag which he himself might introduce before he operates his watch and thus unintentionally introduced into his chart readings.

It is appreciated that different complete operations may involve a large number of steps, events or elements, sometimes only four or five, usually twenty to thirty, and not infrequently several hundred elements are performed by the mechanic, often quickly one after the other and in effect as a continuous movement. It is also appreciated that the time length or time lapse duration of any one of the several elements are never, or at least very seldom, of the same time duration and this tends to introduce a factor of uncertainty into the minds of the testers and tends to constitute a source of error in the recorded times.

For an illustration suppose the first step, event, or element of the mechanic is to pick up a work blank; the second step is to insert the blank in a jig, work holder or other machine part; the third step is to drill the blank; the fourth step is to withdraw the tool from the finished work and the fifth step is to remove the finished work from the machine and lay it down.

Suppose as an actual matter of fact and ignoring any errors due to any personal equation, that it actually takes a total of 0.47 of a minute to complete one operation, divided as follows: 0.06 minute to pick up the blank, 0.07 minute to place it in the machine, 0.15 minute to drill it, 0.13 minute to withdraw the tool from the work and 0.06 minute to remove it from the machine. In theory every highly skilled timestudy engineer or other accurate observer should reach this division of time with an unavoidable and perhaps permissible margin of error, say .0025 of a minute.

The primary object of this invention is to provide apparatus for use in a course of training for the initially unskilled tester or student so that eventually in using the apparatus as herein disclosed he will become so skilled and accurate in ascertaining time lapses in the different steps, events or elements of an observation operation, that his readings will be correct, or differently expressed he will be able to minimize errors which

might otherwise be introduced into his readings due to his personal mental lag or to delay between the instant an event actually occurs due to his muscular reaction or otherwise caused to stop the the running of his stop watch.

Broadly this objective is attained by causing the student under training as hereinafter featured to operate a decimal minute or stop watch, hour after hour, while he observes and make record of prepared events or elements which take place before him, and the true time lapse of which elements is known to the instructor, so that it is possible for the instructor to compare the chart of time intervals presented by the student with the correct answers known to the instructor, and in this way ascertain the progress made by the student as he progressively becomes more and more skilled in his approach to accuracy in observing the simulated sequence of events.

The primary object of the invention insofar as its apparatus aspect is concerned is to provide a simple form of lapsed time indicating machine, characterized in that a movable indicator is divided into distinctive areas dimensioned in the direction of travel of the indicator to represent lapsed time in a series of simulated events or elements and which indicator may be replaced in the machine from time to time to vary the problem presented to the student.

There is disclosed herewith two suggested forms of such apparatus. In the preferred form of apparatus the movable indicator is in the form of a revolving disk, motor driven through speed controlled elements and in which the disk is made up of a plurality of colored segments preferably segments of colored glass, with different arc lengths and disposed to form a circular disk mounted to move past and in momentary registry with a fixed indicator hereinafter sometimes referred to as a zero indicator.

In the other form of apparatus the movable indicator is one of a set of flexible strips resembling motion picture films and provided with colored areas fed past a fixed indicator also referred to as a zero indicator. In this case the film is advanced by a film advancing machine resembling a motion picture projector also provided with speed controlling features.

Various other objects and advantages of the invention will be in part obvious from a consideration of the method features of the disclosure and from an inspection of the accompanying drawing and in part will be more fully set forth in the following particular description of one method of practicing the invention, and the invention also consists in certain new and novel modifications of the preferred method and of other features of construction and combination of parts, hereinafter set forth and claimed.

In the accompanying drawings:

Fig. 1 is a composite view including a perspective showing of one form of apparatus for use in practicing the method aspect of this disclosure, and which apparatus is shown in the form of a portable box arranged to be carried about conveniently from place to place and with parts of its rotating time indicating disk broken away to show normally hidden details of construction, and there is also disclosed a decimal minute watch for use therewith;

Fig. 2 is an enlarged vertical sectional view taken through the apparatus of Fig. 1 in its longitudinal medial plane, and with the parts therein shown somewhat diagrammatically;

Fig. 3 is a fragmentary view largely in front

5 elevation of the upper portion of the disk and adjacent front portion of the device shown in the preceding figures, and with parts of the disk broken away to show component parts of the disk structure and to show the slot in the front of the casing forming the zero indicator;

Figs. 4 and 5 are views of another form of apparatus for practicing the method aspects of the invention and in which Fig. 4 is a view in front elevation of a film resembling a motion picture film except that it is spot colored to form differently colored sections, and Fig. 5 is a view largely in vertical section of portions of an apparatus resembling a motion picture projector for advancing a film and employing the film of Fig. 4.

Referring first to the disclosure of the preferred form of apparatus shown in Figs. 1 to 3, there is disclosed a box-like container 10 provided on its upper side with a handle 11 by means of which the apparatus may be conveniently ported about from place to place where needed. The near right side of the container as shown in Fig. 1 is recessed and the bottom of the recess defined by an upstanding, inset panel board 12 forming one side of a rectangular mechanism containing compartment 13 within the container. The recess is closed by a hinged cover 14 and the cover is secured in closed position by a spring catch 15. The front side 16 of the container 10 forms a light screen and is provided at its upper portion with a narrow vertically extending slot 17 disposed to direct a beam of light from an incandescent lamp 18 contained within the housing and coacting therewith to form a highly illuminated slot is hereinafter sometimes referred to as a zero indicator. A parabolic reflector 19 secured to the rear wall 20 of the container acts to collect light from the source 18 and to project a highly luminous beam of light through the narrow crack-like slot 17. It is the intent here to present a bright line of light as the fixed zero indicator at the twelve o'clock position of the disk hereinafter described and which indicator will be easily visible through the colored disk which at all times is illuminated by the environmental light in the room in which the apparatus operates so as to be visible to the student.

A multi-color disk 20 is mounted to rotate in advance of the front side 16 and its zero-forming slot 17 and is designed to be exposed to view and visible to the student located in front of the apparatus and in position to observe the rotating disk. The disk includes a flat disk-like support 21, preferably a sheet of transparent plastic material, supported on the advanced end 22 of a disk driving shaft 23 to turn therewith. Preferably the forwardly projecting end 22 of the disk shaft is square in cross-section and the plastic disk 21 is provided at its center with a square aperture 24 fitted over the squared shaft end 22. The support 21 is demountably held in place by a retractile spring 25 fitted in and normally projecting from the shaft end 22. The shaft 23 extends through and is supported from the front side 16 by means of an anti-friction mounting 26. The shaft 23 and with the disk 20 is driven from an electric motor 27 mounted within the compartment 13 and the speed of which motor is controlled by a rheostat 28. The control knob 29 of the rheostat is mounted in the panel board 12 and readily accessible for manipulation by the instructor when the cover is in the open position shown in Fig. 1.

As the motor illustrated is preferably of a

high speed type, and it is desired in the instant case to rotate the disk 20 at relatively low speed a reducing gear drive is located between the motor and the disk shaft 23. In the case illustrated the motor shaft 30 is connected to an intermediate shaft 31 through a worm gear drive 32 and the intermediate shaft 31 is connected to the disk shaft 23 by means of a reducing gear drive 33. It is understood from this construction that the motor speed can be regulated and changed from time to time by the instructor manipulating the rheostat so that the disk 20 will be rotated at that speed which is best suited for the skill of the student for the time being facing the disk.

It is within the scope of the disclosure to form the disk 20 of a plurality of different colored segments. This may be attained by coloring or tinting the transparent plastic support 21 or by securing to the rear side of the support patches of thin translucent colored paper or films.

In the device illustrated the disk is formed with a plurality of different segments 34 formed of colored glass or similar semi-transparent or translucent material. Of course it is within the scope of the disclosure to make the disk with the segments permanently fixed thereto and to replace the disk in use from time to time with other similar disks but with different arrangements of the colored segment so as to form different patterns and in this way to vary the problem presented to the student. It is preferable, however, to arrange the disk so that the segments may be replaced or rearranged from time to time as may be desired by the instructor. For this purpose the front of the plastic support 21 is provided with an outer retaining rim 35 which is Z-shaped in cross-section. The rim 35 includes an outwardly projecting flange 36 and an inwardly facing flange 37 dimensioned for overlapping and thus engaging the outer edges of the segments 34 and which rim 35 is demountably secured in position by screws 38 passing through the flange 36 and into the marginal edge of the support 21. Similarly at the hub or center of the support is an inner rim 39 likewise Z-shaped in cross-section. The rim 39 includes an outstanding annular flange 40 for underlapping and thus engaging the inner perimeters of the segments 34 and which rim 39 is secured in place by screws 41 passed through an inwardly extending flange 42 and into the support 21 outwardly of its aperture 24.

It is a feature of this disclosure that the segments be of different arc lengths and that they be of different colors and are usually arranged with highly distinctive colors abutting to form very definite and easily visualized lines of demarcation defining the joints between each adjacent pairs of segments and hereinafter sometimes called time factors. For instance in the fragmentary view shown in Fig. 3 and considering the segments clockwise, segment 43 is blue; 44 is red, 45 is green, and 46 is brown. These segments are sufficiently transparent and so arranged relative to the slot 17 forming the zero indicator that the several indicators will be at all times visible to the student as he looks at the revolving disk. The lines of demarcation, such as the radial line 47 between the blue segment 43 and the red segment 44, are so proportioned in their length dimensions that when they reach their twelve o'clock position they will register exactly one after the other, in alignment with the zero indicator 17 as each

line of demarcation reaches, coincides with and is about to pass the same. As the lines of demarcation are formed by the jointure of the contrasting colors of the adjacent blank spaces it follows that the lines have no width dimension and yet are clearly visible. Of course, the slots 17 and 52 must have sufficient width to permit the light beam to pass therethrough to form the desired bright, fixed indicator. While the intent here is to make the slots of the least practical width to form the indicator, the slots, and thus the fixed indicator, are of course of greater width than the lines of no width dimension. It follows then that at an instant of time each line of demarcation is more or less centered between opposite, definitely formed edges of the fixed luminous indicator the highly skilled operator, watching for the phenomenon, can often detect the instant simultaneous appearance of two streaks of light, one on each side of the momentarily registering line of demarcation.

Another and very important feature of this disclosure is that preferably the entire segment for the time being at the twelve o'clock position or at least its terminal line of demarcation approaching the zero indicator be visible to the student so that he can clearly see the approach of each line of demarcation for some time before it actually reaches the zero mark or indicator at 17. The motor 27 with its rheostat 28, the lamp 18, the control switch SW and socket S are included in a wired circuit (not shown).

In operation and assuming that the apparatus 35 has been plugged into the house current at the socket S, and that the rheostat knob 29 has been set to give the speed desired by the instructor for the particular student for the time using the apparatus, and that one of a selected set of disks 20 is in position, the student assumes a position in advance of the disk similar to that occupied by the skilled engineer in observing an operation in actual practice, in that the student likewise holds a pad of paper and a decimal minute watch DM in one hand and a pencil or pen in the other hand. The disk 20 will be set in motion by closing the main switch SW on the panel board and permitted to rotate until it reaches constant speed. The student starts the watch and observes each succeeding radial line of demarcation 47 as it approaches its twelve o'clock position, and when it exactly coincides with the slot of light forming the zero indicator he presses the watch control button B, reading the indicator sweep hand SH at the instant it stops advancing and notes on his pad the exact time as indicated by the advance of the sweep hand which the current segment took to reach the zero indicator. This is repeated for each 55 succeeding segment to that finally the several time lapses which each segment 34 takes to pass the zero indicator 17 is charted on the student's pad. This is done by the student over and over again until lack of variation in his readings both for each event and for the complete operation assures him that he is at least approaching the correctly timed observations. The instructor compares the student's readings so produced with the chart of known correct times for that particular disk, and notes whenever the student varies from a true reading. For instance, in the illustration above noted when the true total lapsed time should be 0.37 of a minute the student's observed 70 readings should correspond quite closely to the

known time lapses for each event or element which goes to make up the complete operation.

As the student progresses in his skill another and different disk, with say different colors and different arc lengths of segments, is substituted for the one previously used and the exercises repeated as above indicated with different problems to avoid any tendency of the student to memorize any one operation. As the student becomes more and more proficient more complicated disk patterns are used and the speed of disk rotation accelerated. In order to avoid the possibility of the student mentally timing the arrival of the lines of demarcation 41 at the zero indicator, it is suggested that the rheostat 28 be manipulated to vary the speed of the disk 20 from time to time even within a single cycle of rotation.

Referring to the travelling film form of the invention shown in Figs. 4 and 5, it will be understood that a flexible film resembling a motion picture film is used in place of the rotating disk of the preferred form of the invention. The film is fed by some suitable form of film feeding apparatus say by means of an electric motor slowly across the line of vision of the student. In the form of apparatus disclosed in Fig. 5 a film 50 is fed along a film path and across a fixed screen 51 provided with a slot 52 located in the optic axis of a source of light 53, operating with a reflector as suggested, or otherwise disposed to project a beam of light through the slot to form a brightly illuminated zero indicator at 52. In this case the zero indicator is horizontally disposed and extends transversely of the direction of travel of the film as suggested in Fig. 4. In the illustrated instance, the film is fed across the screen 51 by a motion picture projector modified to provide a relatively slow and constant film speed and shown symbolically by the feed sprocket 54 and take-up sprocket 55. Referring to the film 50 as illustrated in Fig. 4, it is noted that it is provided with the usual edge apertures 56 arranged in two lines and adapted to be engaged by the teeth of the sprockets. The film is divided into rectangular colored areas 57 of unequal length measured in the direction of travel of the film. Like the rotary disk of Figs. 1 to 3, the film is semi-transparent and most conveniently is made of the same translucent plastic material of which modern motion picture films are constructed. In the instant illustration and reading from top to bottom the area 58 is blue, 59 is red, 60 is green, 61 is brown and 62 is silver colored. In the illustrated instance the brown area 61 is of the greatest length, the green area 60 is of the least length and the others are of varying lengths therebetween. Each succeeding pair of colored areas form an easily visible line of demarcation 63 which registers with the zero indicator 52 as it overlaps the same for an instant of time with the advance of the film.

It is suggested that the film pass along a path defined by the screen 51 on its rear side and by a fixed face plate 64 forming a structural part of the projector. The face plate is provided with a window 65 the lower edge 66 of which is just beyond the slot 52 in the downward direction of travel of the film indicated by the arrows in Figs. 4 and 5.

In operation the film is fed by the film advancing mechanism of the projector to bring at least one complete area 57 into position vis-

ble to the student through the window 65 as the film passes across the window 65 in the frame of the projector. Here again the succeeding colored areas define easily noticed lines of demarcation 63 and the window 65 is so related to these lines of demarcation so that each of such lines is visible for some distance before they approach the zero point formed by the light showing through the slot 52. In this way the student can watch the approach of each line of demarcation and tension himself to observe the stop watch or decimal minute watch reading at the instant of time the line finally reaches and exactly coincides with the zero point.

As was the case with the Figs. 1-3 form of apparatus the student notes on his writing pad the time lapsed during which each colored area consumes in passing across the zero indicator. The instructor finally compares the student's charts of his observed readings in minutes and fractions thereof for each operation so simulated on each film with the correct prefixed chart of minutes and hundredths thereof known to be correct for the corresponding operation.

The complete equipment for a prescribed course of study includes a set of disks in the case of the Figs. 1-3 disclosure, or a set of films in the case of the Figs. 4-5 disclosure, and each of which sets will contain differently dimensioned and colored areas so that as the student develops in proficiency in solving the time study problems completed more and more difficult problems are presented.

It is suggested that an image of the revolving disk 20 or of travelling film 50 be thrown on a screen following conventional practices in this respect so that a number of students can be trained at the same time by the use of a single apparatus.

I claim:

1. In a device for training time-study students to improve their accuracy in making a chart of stop watch readings of the succeeding events of a simulated operation, the combination of means for forming a long, flat, narrow, sharply defined bright beam of light constituting a fixed luminous indicator on which the student can fixedly focus his eyes, mechanism for replaceably mounting in the device one of a set of traveling indicators each formed of a transparent material, movable in a plane intersecting said fixed indicator and extending substantially perpendicular to the length of the beam, said traveling indicator provided with means forming a series of readily visible, thin, straight lines spaced apart in its direction of movement and forming a plurality of materially more than four blank spaces between the lines, said blank spaces being each indicative by its length measured in its direction of movement of the time lapse of one of the events of the operation simulated by that particular movable indicator, each line registering for at least a portion of its length in parallelism with the fixed indicator for an instant of time, one after the other, as they successively pass through the light beam forming the fixed indicator, the line next to so register at any instant of time being exposed for observation just prior to and up to its point of registering with the fixed indicator, and power mechanism operatively connected to said mounting mechanism for moving the traveling indicator for the time being in the device at a speed sufficiently slow to permit an observer watching the approach of each succeeding line to the fixed indicator to make a stop-watch reading of the

lapsed time since the next preceding line coincided with the fixed indicator.

2. The device defined in claim 1 in which the two spaces between at least one set of three of the succeeding lines are differently colored and of different widths measured in the direction of travel of said traveling indicator and in which the two colored spaces at their jointure form the middle of the three lines as a distinct thin line of demarcation having practically no width dimension and functioning as a definite reading line to indicate the termination of one event and the start of the succeeding event.

3. In a device for training students under the guidance of an instructor to improve their accuracy in making a chart of stop watch readings of the succeeding events of a simulated operation and in which the events are greater than four, the combination of means forming a beam of light constituting a fixed, luminous indicator, an indicator of transparent material guided for movement in one direction across the luminous indicator, provided with a plurality of indicants each designating the termination of one event and the start of the succeeding event, said indicants being spaced apart variable distances in their direction of movement and the distances therebetween being indicative of the relative time lapses which the events consume in passing the luminous indicator, said indicants being of less dimension than that of the luminous indicator as both are measured in the direction of movement of the indicator, means forming an instructor's station including means for driving the movable indicator and a control easily accessible to the operator for varying at will the speed of the movable indicator.

4. In a device of the class described, the combination of a container having a long, narrow slot opening through one wall thereof, a shaft journaled in said wall, extending therethrough adjacent the slot and provided at its outer end with means for replaceably mounting a disk thereon to be driven thereby, mechanism housed within the container for driving the shaft selectively at one of a plurality of constant speeds, a flat disk of transparent material located in advance of said wall and connected by said mounting means to the shaft to be rotated thereby, said disk divided into a plurality of segments with all the segments exposed to view at all times, each adjacent pair of segments being of contrasting colors and forming therebetween straight, thin lines of demarcation extending radially of the disk and successively registering with the slot as the disk rotates, at least one of the segments having an arc distance different from the arc distance of one of its next adjacent segments, and means housed within the container for projecting a beam of light through the slot and through the segments as they move past the slot to form a bright, luminous, definitely defined fixed indicator visible through the segments as they move past the fixed indicator.

5. Apparatus for use in training time-study students to improve their accuracy in reading a stop watch, including a container, an annular disk carried by the container exteriorly thereof, extending vertically and mounted for rotary movement about a horizontal axis, said disk comprising differently colored transparent segments in edge-to-edge abutting relation and the entire area of each segment being at all times exposed to view to permit the student operating a stop watch in advance of the disk to pick out any one of the segments for clocking the same, each pair of adjacent segments forming therebetween a

distinctive and easily followed radial line of demarcation having such width dimension as would be formed by a joint between the different abutting segments, said container including a wall located back of the disk, said wall provided with a long, narrow slot with which the lines of demarcation exactly register in parallelism one after the other as the disk is rotated, means within the container for directing a beam of light through the slot to form a bright, luminous, fixed indicator visible through the several colored segments as they pass the same, an electric motor for driving the disk, and a control for resetting said motor speed to provide at will for a different disk speed.

6. Apparatus for use in training time-study students to improve their accuracy in reading a stop watch to measure the time duration of a plurality of elements or events which go to make up an operation, said apparatus including a structural wall forming a fixed opaque screen provided with a long, narrow slot, a movable indicator fashioned to pass in front of the slot and presenting a plurality of colored areas each representing by its length in the direction of travel of the movable indicator the lapsed time of one of the events of a simulated operation and collectively representing the sum of the lapsed time duration of all of the events which go to make up the simulated operation, the areas forming adjacent pairs being of contrasting colors and forming therebetween straight, easily visible lines of demarcation of less width than the slot, means in rear of the wall for directing a beam of light through the slot to form a long, flat, fixed, luminous indicator visible as a line through the movable indicator, said lines of the movable indicator, one after the other, registering with the slot for an instant time, and power means for advancing the movable indicator through said beam of light.

7. The article defined in claim 6 in which the movable indicator is a multi-colored disk whose blank colored areas are of segmental form and of various arc lengths and whose lines of demarcation extend in relatively radial directions.

8. Apparatus for use in preparing a record in fractions of a standard unit of time, of the time lapses of a series of elements of a simulated operation in the training of students to read and operate a stop watch, which is calibrated into fractions of a standard unit of time for direct reading, said apparatus including a display device for simulating the time duration of the elements of an operation, said device including a screen provided with a long slot opening therethrough, a movable indicator of transparent material formed with a plurality of blank areas of different colors in edge-to-edge relation with adjacent blank areas being differently colored to provide lines of demarcation, means for directing a beam of light through the slot and through the indicator to form a luminous, fixed indicator visible from a position in advance of the display device as a thin, bright line, means for moving the indicator and with it the colored areas at a preset speed across the beam of light from the slot, each colored area dimensioned in its direction of travel when at such speed to pass the slot in a period of time which is an exact multiple of said fraction of a standard unit of time.

9. An article of manufacture constituting a movable indicator for use as a replaceable unit in a projection machine of the type in which the indicator moves across a narrow, flat beam of

light fixed in space and functioning as a bright, fixed, luminous indicator; said movable indicator provided with means for engagement by a driving element of the machine for advancing the indicator in one direction at constant speed, said indicator being of a material sufficiently transparent to permit the light from the machine to pass therethrough, and said indicator being divided in its direction of movement into a plurality of differently colored blank areas, each pair of adjacent areas being of contrasting colors and forming therebetween thin, straight lines of demarcation, at least two of the adjacent areas having different widths measured in the direction of travel of the movable indicator.

10. The article defined in claim 9 in which the movable indicator is in the form of a motion picture film provided with edge apertures, in which the blank colored areas are of a rectangular form and whose lines of demarcation extend parallel to each other in spaced-apart relation at right angles to the length of the film.
